US0D1087926S

(12) **United States Design Patent** (10) Patent No.: **US D1,087,926 S**
(45) Date of Patent: **** Aug. 12, 2025**

(54) **SMALL REMOTE OPERATING DEVICE FOR AN AUTOMATIC DOOR CONTROLLER**

(71) Applicant: **The Chamberlain Group LLC**, Oak Brook, IL (US)

(72) Inventors: **Matthew James Baer**, Forest Park, IL (US); **Jeremy Abel**, West Dundee, IL (US); **Jonathan Lee**, La Grange, IL (US)

(73) Assignee: **THE CHAMBERLAIN GROUP LLC**, Oak Brook, IL (US)

(**) Term: **15 Years**

(21) Appl. No.: **29/944,923**

(22) Filed: **May 30, 2024**

(51) LOC (15) Cl. **14-03**

(52) U.S. Cl.

USPC **D13/168**

(57) **CLAIM**

The ornamental design for a small remote operating device for an automatic door controller as shown and described.

DESCRIPTION

FIG. 1 is a front isometric view of a first embodiment of a small remote operating device for an automatic door controller.

FIG. 2 is a back isometric view thereof.

FIG. 3 is a front side elevation view thereof.

FIG. 4 is a back side elevation view thereof.

FIG. 5 right side elevation view thereof.

FIG. 6 is a left side elevation view thereof

FIG. 7 is a top view thereof; and,

FIG. 8 is a bottom view thereof.

1 Claim, 8 Drawing Sheets
